UNITED STATES PATENT OFFICE.

LOUIS G. SEDBERRY, OF WETUMPKA, ALABAMA.

RAILWAY-TIE AND MEANS FOR SECURING RAILS THERETO.

No. 893,941.

Specification of Letters Patent.

Patented July 21, 1908.

Application filed April 22, 1907. Serial No. 369,692.

To all whom it may concern:

Be it known that I, LOUIS G. SEDBERRY, citizen of Alabama, residing at Wetumpka, in the county of Elmore and State of Alabama, have invented certain new and useful Improvements in Railway-Ties and Means for Securing Rails Thereto, of which the following is a specification.

This invention comprises a novel form of railroad tie embodying a combined construction of plastic material, preferably concrete, and metal.

The object of the invention is to provide a tie constructed as above mentioned and in the practical embodiment of which, to a certain extent, the customary advantages of the wooden tie, with reference to cushioning qualities and resiliency, will be secured.

The invention includes, furthermore, novel means for securing rails to the tie, which means will be more specifically described hereinafter.

For a full understanding of the invention and the merits thereof and also to acquire a knowledge of the details of construction of the means for effecting the result, reference is to be had to the accompanying drawings and following description, in which:

Figure 1 is a perspective view of a tie and rail securing means embodying the invention; Fig. 2 is a vertical sectional view taken on the line 2—2 of Fig. 3; Fig. 3 is a front elevation of the tie, partially broken away showing the rail securing means at one side of the rail, in section, and the similar means at the opposite side of the rail in elevation; Fig. 4 is a vertical sectional view similar to Fig. 2, taken on the line 4—4 of Fig. 5; Fig. 5 is a view similar to Fig. 3 showing the construction disclosed in Fig. 4; Fig. 6 embodies a further modification of the invention; Fig. 7 is a top plan view bringing out more clearly the construction shown in Fig. 5; Fig. 8 is a view similar to Fig. 7 but showing the construction of the modification in Fig. 6; Fig. 9 is a detail perspective view of one of the clamps shown in Fig. 1; Fig. 10 is a detail perspective view of one of the clamps shown in the modification in Fig. 4; Fig. 11 is a detail view of one of the clamps shown in the modification in Fig. 6, and Fig. 12 is another view of the clamp shown in Fig. 11.

Corresponding and like parts are referred to in the following description and indicated in all the views of the drawing by the same reference characters.

Specifically describing the invention, and referring to the construction shown in Figs. 1, 2, and 3, inclusive, the numeral 1 indicates a tie which is of plastic material such as concrete, or the like. In the body of the tie 1 is molded or otherwise embedded or applied, a metal beam or body 2. The beam 2 may be described to be of the usual I-form comprising a central vertical web and opposite heads 60 formed longitudinally of the said web, said heads being designated 2^a. The beam 2 has the lowermost of its heads 2^a and nearly the whole of the web connecting the heads 2^a embedded in the plastic material of the tie 1, 65 the uppermost head 2^a, however, being arranged slightly above the top of the tie with its opposite longitudinal edge portions spaced therefrom. The beam 2 of the tie 1 is designed to support the rails 3 which may be 70 disposed upon the tie, under actual conditions of service, peculiar means being employed to attach the rails thereto.

As shown in Fig. 1 the securing means for the rails 3 comprise opposite engaging members 4 each of said members being provided with an upwardly curving flange 5 engaging over the adjacent portion of the base of the rails 3, and each member 4 being also provided at its longitudinal edges with downwardly projecting flanges 6 adapted to engage beneath opposite side portions of the upper head 2^a of the beam 2. Each engaging member 4 consists of a plate having its longitudinal edges bent downwardly to form 80 flanges engaging opposite edge portions of the head 2^a of the beam 2, and the end of each member 4 being bent upwardly at an inclination to overlap the base of the rail 3. The flanges of the base 4 are extended beneath the upwardly inclined ends thereof and in spaced relation thereto so as to engage beneath the rails 3 in the manner shown. It will be apparent that the engaging members 4 may move longitudinally of the beam 85 90 95 100 105 110 115 120 125 130 135 140 145 150 155 160 165 170 175 180 185 190 195 200 205 210 215 220 225 230 the engaging members 4, should the latter be used in coöperation with rails of different sizes. An end portion of each of the clamp plates 7 extends over the outer portion of the 5 adjacent engaging members 4 with which it coöperates.

Figs. 4, 5, and 7, embody a modification of the invention in which the engaging members 4^a are secured in position upon the upper head 2^a of the beam 2 by special means. 10 In this instance, the engaging members 4^a are each provided at the sides 6 thereof with downwardly extending flanges 6^a having lateral openings therethrough. Wedges 10 are 15 adapted to be forced through the openings in the flanges 6^a, and through openings in the web or central portion of the beam 2, in order to secure the members 4^a to the beam 2, and in engagement with the rail 3. The 20 wedges 10 are shown most clearly in Figs. 5 and 7 and it will be noted that said wedges not only comprise means for securing the members 4^a from displacement from the beam 2 but they coöperate to effect movement thereof on the beam 2 to cause the latter to engage hard against the base of the rail with which they coöperate. When the wedges have been inserted and properly operated upon to secure the members 4^a and 30 the rails 3 in position upon the beam 2, the smaller extremities of said wedges are turned laterally as shown at 10^a to prevent accidental displacement of these members.

The modified adaptation of the invention 35 shown in Figs. 6 and 8, is substantially the same embodiment thereof as disclosed in that just above described. In this instance, however, the engaging members 11 are made of cast metal, being secured in place by 40 wedges 12 coöperating therewith in substan-

tially the same manner, as the members 10 co-act with the members 4^a above described. In the construction shown in Figs. 6 and 8 the members comprising the invention are formed for the purpose of giving a maximum 45 amount of rigidity and strength, after the same have been applied to the tie and in co-operation with the rails. In this instance a main rail and guard rails, designated 3, are shown, and a filler-block 13 is interposed between said rails. This construction is one which is common in railroad structure, so far as the general arrangement of the parts is concerned.

Having thus described the invention, what 55 is claimed as new is:

In combination with a tie including a longitudinal head, a rail seated thereon, engaging members applied to the head at opposite sides of the rail, each engaging member consisting of a plate having its longitudinal edges bent downwardly to form flanges engaging the head at opposite edges thereof, an end of each engaging member being bent upwardly at an inclination so as to overlap the 60 adjacent basal portion of the rail and the flanges thereof being extended beneath the inclined end and spaced therefrom in engagement with the underside of the rail base, and members secured to the head of the tie, 65 to hold the engaging members aforesaid in an adjusted position in engagement with the rail.

In testimony whereof I have affixed my signature in presence of two witnesses.

LOUIS G. SEDBERRY.
